UNITED STATES PATENT OFFICE.

JACOB WEIDENMANN, OF HARTFORD, CONNECTICUT.

IMPROVEMENT IN BURIAL-CASES.

Specification forming part of Letters Patent No. 123,599, dated February 13, 1872.

SPECIFICATION.

I, JACOB WEIDENMANN, of Hartford, in the county of Hartford and State of Connecticut, have invented a new and useful Burial-Case, of which the following is a specification, reference being had to the accompanying drawing, in which—

Figure 1 is a side elevation of the burial-case with the side of the exterior wooden box, which is next the observer, removed.

Fig. 2 is a similar end view. Fig. 3 is an exterior perspective view. Fig. 4 is a detached enlarged view in section of the standards, which support the coffin from beneath. Fig. 5 is a detached enlarged view of the guides attached to the side of the interior of the covering-box. Fig. 6 is a view, in section, of the part shown in Fig. 5, through the dotted line $x x$. Fig. 7 is a perspective view of one of the angle-irons attached to the insides of the exterior box to serve as markers.

To preserve the bodies of dead friends appears to be a cherished idea—at least, with Americans. To effect this, various costly expedients have been resorted to, such as building brick-graves, covering coffins with a large body of cement, and the like. The present invention is an attempt to make a cheap, effective, and durable, impermeable covering for coffins and caskets.

The letter a indicates a common coffin, and b is a common coffin-box, except that it has a lid with perforations, and has certain attachments shortly to be described. It is made somewhat larger than those heretofore used. On the bottom of the box are set standards, made, preferably, of cast-iron; generally four in number, on which the coffin rests. These standards c are hollow, and have perforations c' so as to permit the escape of air when the inclosing substance is put around the coffin. To the sides and ends of the interior of the box are attached guides d , preferably of cast-iron, which prevent the coffin from touching the box on the sides and ends. The coffin be-

ing thus set into the box the lid, having openings b' , is fastened on, and cement, plaster of Paris, or other similar material made into a thin paste, is poured into the openings in the lid till the box is full; and this substance, when set hermetically, seals the coffin from air and water.

It may be desirable at some future time to open the coffin thus sealed up. To facilitate this, there are angle-irons e fastened at intervals along the sides and ends of the interior of the box, their horizontal parts on a level with and pointing straight toward the joining of the coffin and its lid. The first step in opening the coffin after once sealed up in cement, as described, would be to split away the exterior box. These angle irons would come away with the sides and ends, and thus leave holes in the cement, marking the line where the cement must be split to come at the joining of the coffin and its lid, for which reasons I have called them "markers." The holes left by the markers will serve as handy openings in which to insert wedges to split the cement.

If it is desired to use the cement very thin it will probably be advisable to put two or more downward-projecting spurs on the under side of the lid of the outer box, so as to hold the coffin down in place, as in a very thin paste it might be floated off the standards underneath.

I claim as my invention—

1. The burial-case, as described, consisting of an interior coffin, and an outer case with the space between filled with cement or the like poured or put in, in a fluid or plastic state.

2. The standards c and guides d , constructed and used, substantially as described, for the purposes set forth.

3. The "markers" e , constructed and used substantially as set forth.

J. WEIDENMANN.
